Application December 27, 1938, Serial No. 247,736

9 Claims. (Cl. 62—108.5)

This invention relates to freezing trays, especially to the portable type adapted for use in household refrigerators.

An object of this invention is to provide a very simple and efficient form of mechanically operated tray from which the frozen ice blocks may be readily removed without melting the ice loose from the pan or grid.

This invention provides various improvements over the ice tray disclosed in a prior application Ser. No. 98,213, filed August 27, 1936, by Donald H. Reeves, and assigned to the assignee of this application.

One feature of the partitioning grid of this invention is the actuating hand lever arrangement whereby the hand lever is mounted intermediate the two ends of the longitudinally extending actuating bar and moves said actuating bar longitudinally by exerting a pull upon one portion thereof and a thrust upon the opposite portion thereof.

Another feature is the simple and efficient force-multiplying mechanism between the hand lever and the actuating bar which permits a very simple and economical method of assembling the grid parts.

Another feature is the slot arrangement between the longitudinal main partition and the series of loosely spaced cross partitions whereby said cross partitions may be readily assembled upon said main partition by tilting them laterally from their normal position and later tilting said cross partitions back and loosely retaining them in their normal non-laterally-tilted position.

Another feature is the slot arrangement between the cross partitions and the longitudinal actuating bar whereby said actuating bar and said cross partitions may be readily assembled together and thereafter mutually retain each other in their assembled positions. This feature renders unnecessary any guide pins and slots or other similar devices at either end of the actuating bar and hence materially simplifies the structure.

Another feature is the use of a single actuating bar for moving all the cross partitions longitudinally to loosen the ice blocks by moving said actuating bar both upwardly away from ice and longitudinally relative to the main longitudinal partition. The upward movement or raised position of the actuating bar gives it an increased leverage upon the cross partitions and thus facilitates the tilting of said cross partitions.

Further objects and advantages of the present

invention will be apparent from the following description, reference being had to the accompanying drawings wherein a preferred embodiment of the present invention is clearly shown.

In the drawings:

Fig. 1 is a plan view of the grid and pan of this invention, all the parts being in freezing position.

Fig. 2 is a vertical section on line 2—2 of Fig. 1.

Fig. 3 shows the grid removed from the pan and the hand lever having been rotated about 90 degrees to partially tilt the cross walls longitudinally relative to the main longitudinal wall.

Fig. 4 is similar to Fig. 3 but shows the parts in position when the hand lever is rotated to its maximum ice-ejecting position.

Fig. 5 is a section on line 5—5 of Fig. 3.

Fig. 6 is a section on line 6—6 of Fig. 1 on a larger scale, but with the actuating hand lever omitted.

Figs. 7 to 14 are detail views.

Fig. 7 is a plan view of the hand lever.

Fig. 8 is a side elevation of the hand lever.

Fig. 9 is an end view of the hand lever.

Fig. 10 is a plan view of a die cast fitting which connects the hand lever to the actuating bar.

Fig. 11 is a side elevation of the die cast fitting.

Fig. 12 is a vertical section on line 12—12 of Fig. 11.

Fig. 13 is a plan view of the actuating bar.

Fig. 14 is a face view of one of the cross partitions.

Similar reference characters refer to similar parts throughout the several views.

Numeral 10 designates the container pan, which is preferably drawn in one piece from flat sheet aluminum or aluminum alloy and is preferably slightly flexible so that it may be more readily loosened from its frozen contents. A flange 11 may be provided around the upper marginal edge of pan 10 to better its appearance and to avoid an otherwise sharp edge of metal around the top edge of the pan.

The removable partitioning grid 20 comprises a main longitudinal wall 21, which preferably but not necessarily lies centrally located in pan 10, and a series of longitudinally spaced cross walls 22 loosely mounted thereupon to divide the pan contents into smaller ice-block compartments. The main wall 21 has a series of open slots 23 extending upwardly from its bottom edge to loosely receive the continuous portions 24 of cross walls 22, while the cross walls 22 each has an open slot 25 extending down from

its upper edge to loosely receive the continuous portions 26 of the main wall 21 above slots 23. Preferably the slots 23 are shaped with an inclined rear edge 27 (as shown in the drawings) and a quite narrow mouth so that when cross walls 22 are swung back against the inclined edge 27 the lower edge of each cross wall 22 will abut the bottommost forward edge 28 of its slot 23 (see Fig. 2). Thus the rearward tilting of each cross wall 22 in its slot 23 is positively limited by the inclined edge 27 and abutment 28. This feature is of importance as will be later seen.

The open slots 25 in cross walls 22 are preferably shaped as clearly shown in Fig. 14. To assemble the main and cross walls together the main wall 21 may be first inclined relative to the cross walls 22 and passed thru the opening 30 in each cross wall, after which said main wall is moved to its vertical position shown in Fig. 5 where the small laterally projecting tongue 31 on each cross wall overlies said main wall 21 and so prevents each cross wall from dropping due to gravity from its position shown in Fig. 5.

Each cross wall 22 also is cut away to provide a large central notch 35 therein and two opposed marginal tongues 36 and 37 partially overlying central notch 35. The longitudinally extending actuating bar 40 has a series of pairs of notches 41 cut therein, so that said actuating bar 40 may first be tilted laterally and inserted past the tongues 36 and 37 into the notches 35 in cross walls 22, after which the bar 40 may be then turned to its final horizontal position as clearly shown in the drawings (see especially Figs. 1 and 5). When actuating bar 40 is in this assembled position on cross walls 22, the tongues 36 and 37 on the cross walls overlie bar 40 and so prevent the direct upward withdrawal of bar 40 from notches 35. At the same time the bar 40, when retained in place by the hand lever mechanism described hereinafter, will prevent any such lateral shifting or tilting of cross walls 22 relative to the main wall 21 as will permit main wall 21 to again slide out of the assembling opening 30. In other words, the bar 40 by bearing laterally against the sides of notches 35 loosely retains cross walls 22 in their proper assembled position upon the main wall 21. It is to be understood that sufficient clearances are provided in all the notches and slots so far described as to provide a quite loose fit between the main wall 21, the cross walls 22, and the actuating bar 40, so that when the bar 40 is moved longitudinally relative to main wall 21 the cross walls 22 will be readily tilted forward (or to the left as seen in Figs. 1 to 4) by the engagement therewith of notches 41 in bar 40. Preferably but not necessarily the notches 41 have progressively greater longitudinal widths from the left end to the right end of bar 40 (as seen in Figs. 3 and 13) so that the full actuating force of bar 40 is first applied to the leftmost cross wall 22, then applied successively to the other cross walls 22 toward the right to tilt them toward the left one after the other. This progressive action in releasing the ice blocks reduces the force necessary to be applied to move the actuating bar 40.

Any suitable presently known force-multiplying mechanism may be used to move the actuating bar 40 longitudinally of the main wall 21 to tilt the cross walls 22 as above described. However the hand-lever mechanism illustrated in the drawings is preferred since it is especially simple in structure and highly efficient in operation, and at the 75

same time may be readily assembled with the parts described above in a very simple and economical manner, as will now be described. The die-cast hand lever 50 has a slot 51 therein which fits snugly over the upstanding projection 52 on the main wall 21 and is pivoted thereto by means of pivot pin 53 whose two ends lie flush with the side surfaces of hand lever 50 (see Fig. 5). Hand lever 50 has cast integral therewith two laterally projecting journals 55 which serve as eccentric or crank pins for giving the actuating bar 40 a lifting and longitudinal movement relative to main wall 21. These two eccentric journals 55 fit into two aligned bearing notches 56 in the die cast fitting 60 which is rigidly fixed to actuating bar 40 by any suitable means. Hence when hand lever 50 is rotated from its freezing position shown in Figs. 1 and 2 to its maximum ejecting position shown in Fig. 4, the eccentric journals 55 will move in an arc about the stationary pivot pin 53 as a center and consequently move the central portion of actuating bar 40 in a corresponding arc.

An important feature of the hand lever and its associated mechanism is the simple method of assembling these parts to the grid after the assembling together of main wall 21, cross walls 22, and actuating bar 40 as above described. The main body of the die-cast fitting 60 overlies bar 40 but it has a portion 61 which snugly fits down into a quite wide central opening 62 (see Figs. 6 and 13) in bar 40. Fitting 60 is rigidly fixed to bar 40 by an underlying lug 63 at its rear end which may be inserted in place by a slight tilting of fitting 60, and a downwardly extending projection 64 at its forward end which may be inserted downwardly thru hole 65 in bar 40 and then staked over on the under side thereof, as shown at 66 in Fig. 6.

Now in order to assemble all the grid parts together, the procedure may be as follows: the main wall 21, the cross walls 22 and the actuating bar 40 are first loosely assembled together as described above. Next the slot 51 in hand lever 50 is passed over the projection 52 on main wall 21 and the pivot pin 53 is inserted with its ends lying flush with the straight sides of lever 50. Next the fitting 60 is passed downwardly over the outer end of lever 50 by threading said lever thru the central opening 67 in fitting 60 until the two opposed journals 55 on lever 50 enter and seat properly in the two laterally aligned bearing notches 56 in fitting 60 (see Figs. 6 and 11), and at the same time fitting 60 is tilted slightly to permit its rear lug 63 to be inserted snugly under bar 40 and thereafter the forward projection 64 on fitting 60 is passed thru the hole 65 in bar 40 to permit fitting 60 to lie flat upon bar 40 in its final position. The final operation which retains all the assembled parts together and prevents accidental disassembling thereof is the simple staking over of the projection 64 on the under side of bar 40 as shown at 66 in Fig. 6. When thus assembled, the snug fit of slot 51 in handle 50 over the flat projection 52 on main wall 21 permits hand lever 50 to swing only in a longitudinal plane, and consequently the two opposed journals 55 on hand lever 50 will likewise limit the actuating bar 40 either to vertical tilting or to bodily movement in a vertical longitudinal plane since fitting 60 is fixed to bar 40. Obviously bar 40 cannot be thereafter tilted laterally sufficiently to permit its removal from the notches 35 in cross walls 22 even though bar 40 be previ-

ously assembled to cross walls 22 by such lateral tilting thereof.

It will be noted in the drawings that journals 55 appear to overlap or interfere with the pivot pin 53 (see especially Fig. 6) due to the small eccentricity of said journals 55 on lever 50. In reality they do not interfere because these journals 55 are cut away at 57 to permit pin 53 to be fully cylindrical. The cut away portions 57 of journals 55 permits the lateral insertion of the round pin 53 into its bearing hole in lever 50. If pin 53 has a sufficiently loose fit in its hole as to permit it to move endwise therein it may accidentally be moved endwise so as to partially project into notch 56 in fitting 60 in one position thereof, and thus cause jamming of the mechanism. In order to prevent this, two small lateral inwardly projecting ears 42 are provided on bar 40 opposite the notches 56 in fitting 60 to retain pivot pin 53 against such accidental endwise movement when said notches 56 are in aligned position with pin 53.

The operation of the tray and grid is as follows: The grid 20 is set loosely in pan 10 with the lever 50 and all other parts in position as shown in Figs. 1 and 2. In this position the upper portions of the cross walls 22 will be tilted back by the forward edges of notches 41 in bar 40 until such backward tilting is limited by the rear surface of said cross walls 22 abutting the inclined edge 21 of slots 23 and the bottom forward surface of walls 22 abutting the abutments 28 on main wall 21. Thus all the cross walls 22 will be positively tilted backward and retained at the same angle when in freezing position, and at the same time all the cross walls will be held against the forward edges of notches 41 in bar 40, as clearly shown in Fig. 2. The pan 10 may be filled with water to the desired level, either before or after grid 20 is inserted therein, and inserted into a freezing chamber until the ice is hard frozen with the grid parts still in their positions shown in Fig. 2.

To remove the frozen ice blocks, the tray is removed from the freezing chamber and the hand lever 50 rotated upwardly, as shown in Figs. 3 and 4, to force the actuating bar 40 first upwardly and toward the left, according to the arcuate movement of journals 55 about pin 53 as a center. The left-most cross wall 22 will be tilted forward against the two ice blocks at the left end of pan 10 (as seen in Figs. 1 to 4) by the engagement of notch 41 in bar 40 and cause these two blocks to loosen from the grid walls 21 and 22 and be forced upwardly along the inclined end wall 12 of pan 10, where they may be then picked up with the fingers.

If desired, the two rear edges of each pair of notches 41 in bar 40 may be staggered slightly so that the upper portion of one half of each cross wall 22 will be tilted forward by bar 40 slightly before the other half thereof, this being permitted by a slight flexing of the slightly flexible cross walls 22. This successive tilting of the two opposite halves of each cross wall greatly facilitates the operation since almost the entire force of bar 40 is applied to a single ice block at one time. The small neck of ice in the unfilled portion of slot 23 will be crushed and forced out laterally, which action will aid somewhat in loosening the two ice blocks from the main or center wall 21.

Next the second cross wall 22 is engaged by the second slot 41 in bar 40 and similarly tilted forward to release its two ice blocks in a similar

manner, and so on until all the cross walls 22 have been successively tilted forward by being engaged with the rear edges of the progressively wider notches 41 in bar 40. In order for this action to be uniformly successive it is clear that all the cross walls should be retained adjacent the forward edges of the actuating notches 41 during freezing. After each cross wall is loosened from the ice by pivoting about its bottommost edge, it is then quite loosely retained relative to the main wall 21 by the abutment 28 and hence is readily moved out of the way and does not prevent the ejecting movement of the next two ice blocks immediately therebehind.

In order to insure the loosening of the last two ice blocks from main wall 21 by the tilting forward of the last cross wall 22, the last notch 23' in main wall 21 is shaped differently from the other notches 23 so that the last cross wall 22 will pivot about an abutment 28' located materially above its bottommost edge (see Fig. 4). Hence when said last cross wall 22 is tilted forward by bar 40 about the raised pivot abutment 28', its lower portion 22' will kick back or be forced to move rearwardly against the last two ice blocks and so loosen them from main wall 21.

In Fig. 3 the lever 50 has been moved only about 90 degrees, but all the cross walls 22 have been tilted forward to some extent since even the last cross wall is shown tilted a very small angle from its freezing position. The further movement of hand lever 50 to its maximum ejecting position of Fig. 4 permits a wide angle swinging of all the cross walls to almost a vertical position in order to increase the tendency for all the loosened ice blocks to drop from the grid by gravity by merely vertically shaking the grid. Such vertical shaking of the grid can be very readily done by the one hand which grasps the hand lever 50 since said lever 50 is centrally located approximately above the center of gravity of the grid. This is a very advantageous feature of this invention.

If desired, a small downward projection 69 may be provided on the projection 64 on fitting 60 (see Fig. 4) which will serve as a positive stop by contacting the upper edge of main wall 21 when lever 50 is swung to its maximum ejecting position. Thus the actuating bar 40 is at all times positively spaced above the top edge of main wall 21.

In Figs. 1 and 2 there is shown a small slightly flexible curved sheet metal handle 70 which is pivoted to pan 10 by means of pivot pin 71 which is journaled in a small pressed metal channel bracket 72 which may be spot welded to the end wall of pan 10. When handle 70 is in its raised position as shown in Fig. 2, its lower cam portion 75 will rest loosely upon the support for the pan 10. Hence by pressing down upon the top of handle 70 the curved cam portion 75 thereof will ride upon the support upon which pan 10 rests and thus force this end of the pan up from its support. This is a very simple and efficient means for loosening the pan 10 from its frozen bond to its support.

Preferably all the ice contacting surfaces of both pan 10 and the grid 20 are of anodized aluminum and impregnated or coated with a strongly adhering high-melting-point wax or other water-shedding material. This will greatly reduce the strength of the frozen bond of the ice to the contacting metal surfaces and hence greatly facilitate the above described operation.

While the embodiment of the present invention

as herein disclosed constitutes a preferred form, it is to be understood that other forms might be adopted, all coming within the scope of the claims which follow.

What is claimed is as follows:

1. In a freezing device, a container pan and a partitioning grid for said pan, said grid comprising: a main longitudinal wall, a series of cross walls cooperating with said main longitudinal wall to form ice block compartments and being movable relative to said main longitudinal wall, an actuating bar mechanically associated with said cross walls so as to move said cross walls longitudinally relative to said main wall, and a hand lever pivotally mounted upon said main wall adjacent the longitudinal center of said actuating bar and reacting between said main wall and actuating bar to cause relative longitudinal movement therebetween by exerting a pull upon approximately one-half of said bar and a thrust upon the other half thereof.

2. In a freezing device, a container pan and a partitioning grid for said pan, said grid comprising: a main longitudinal wall, a series of cross walls cooperating with said main longitudinal wall to form ice block compartments and being movable relative to said main longitudinal wall, an actuating bar overlying said main wall, and a force-multiplying means located intermediate the end portions of said bar and reacting between said bar and main wall to cause relative longitudinal movement therebetween by exerting a pull upon one portion of said bar and a thrust upon the other portion thereof, said actuating bar being mechanically associated with said cross walls so as to move said cross walls relative to said main wall.

3. In a freezing device, a container pan and a partitioning grid for said pan, said grid comprising: a main longitudinal wall, a series of cross walls cooperating with said main longitudinal wall to form ice block compartments and being movable relative to said main longitudinal wall, said cross walls having aligned open notches extending thru the upper edges thereof, an actuating bar having portions lying within said open notches and engaging the lateral margins thereof so as to move said cross walls longitudinally upon the longitudinal movement of said bar, said open notches being of such depth as to permit substantial vertical displacement of said bar therein, and force-multiplying means for moving said bar both vertically and longitudinally relative to said main wall, whereby to facilitate the removal of the frozen ice blocks.

4. In a freezing device, a container pan and a partitioning grid for said pan, said grid comprising: a main longitudinal wall, a series of cross walls cooperating with said main longitudinal wall to form ice block compartments and being movable relative to said main longitudinal wall, said cross walls having aligned openings adjacent their upper edges, an actuating bar having portions lying within said aligned openings and engaging at least two margins of each of said openings so as to move said cross walls longitudinally upon the longitudinal movement of said bar, said aligned openings being of such depth as to permit substantial vertical displacement of said bar relative to said cross walls, and force-multiplying means for moving said bar vertically and longitudinally whereby said cross walls are moved longitudinally to facilitate the removal of the frozen ice blocks.

5. In a freezing device, a container pan and a

partitioning grid for said pan, said grid comprising: a main longitudinal wall, a series of cross walls cooperating with said main longitudinal wall to form ice block compartments and being movable relative to said main longitudinal wall, said cross walls having aligned openings adjacent their upper edges, an actuating bar having portions lying within said aligned openings and engaging at least two margins of each of said openings so as to move said cross walls longitudinally upon the longitudinal movement of said bar, said aligned openings being of such depth as to permit substantial vertical displacement of said bar relative to said cross walls, and a crank mechanism reacting between said bar and main wall for moving said bar both vertically and longitudinally relative to said main wall to facilitate the removal of the frozen ice blocks.

6. In a freezing device, a container pan and a partitioning grid for said pan, said grid comprising: a main longitudinal wall, a series of cross walls cooperating with said main longitudinal wall to form ice block compartments and being movable relative to said main longitudinal wall, said cross walls having aligned openings adjacent their upper edges, an actuating bar having portions lying within said aligned openings and engaging at least two margins of each of said openings so as to move said cross walls longitudinally upon the longitudinal movement of said bar, said aligned openings being of such depth as to permit substantial vertical displacement of said bar relative to said cross walls, and a crank mechanism for bodily lifting said bar upwardly away from the ice contents and moving said bar longitudinally whereby said cross walls are moved longitudinally to facilitate the removal of the frozen ice blocks.

7. In a freezing device, a container pan and a partitioning grid for said pan, said grid comprising: a main longitudinal wall, a series of cross walls cooperating with said main longitudinal wall to form ice block compartments and being movable relative to said main longitudinal wall, said cross walls having aligned openings adjacent their upper edges, an actuating bar having portions lying within said aligned openings and engaging at least two margins of each of said openings so as to move said cross walls longitudinally upon the longitudinal movement of said bar, said aligned openings being of such depth as to permit substantial vertical displacement of said bar relative to said cross walls, and force-multiplying means located intermediate the end portions of said bar and reacting between said bar and main wall for lifting said bar vertically and moving said bar longitudinally relative to said main wall to facilitate the removal of the frozen ice blocks.

8. In a freezing device, a container pan and a partitioning grid for said pan, said grid comprising: a main longitudinal wall, a series of cross walls cooperating with said main longitudinal wall to form ice block compartments and being movable relative to said main longitudinal wall, said cross walls having aligned open notches extending thru the upper edges thereof, an actuating bar having portions lying within said open notches and engaging the lateral margins thereof so as to move said cross walls longitudinally upon the longitudinal movement of said bar, said open notches being of such depth as to permit substantial vertical displacement of said bar therein, and crank mechanism for vertically displacing said bar within said notches and mov-

ing said bar longitudinally relative to said main wall, whereby to facilitate the removal of the frozen ice blocks.

9. In a freezing device, a container pan and a partitioning grid for said pan, said grid comprising: a main longitudinal wall, a series of cross walls cooperating with said main longitudinal wall to form ice block compartments and being movable relative to said main longitudinal wall, said main wall having slots extending upward from its bottom edge to loosely receive said cross walls, said cross walls having laterally inclined permanently open slots extending down-

ward from their top edges to loosely receive said main wall and permit ready assembling together of said main wall and cross walls by laterally inclining said main wall, said cross walls having laterally extending shoulders adjacent said inclined slots which shoulders overlie said main wall when in finally assembled position and thereby to loosely retain said cross walls against dropping away from said main wall due to gravity.

HARVEY D. GEYER.
FREDERICK W. SAMPSON.
